UNITED STATES PATENT OFFICE.

SAMUEL N. McCLEAN, OF CLEVELAND, OHIO, ASSIGNOR, BY MESNE ASSIGNMENTS, TO
THE AUTOMATIC ARMS COMPANY.

GAS-OPERATED GUN.

1,003,632.

Specification of Letters Patent. Patented Sept. 19, 1911.

Application filed October 14, 1905, Serial No. 282,779. Renewed November 27, 1909. Serial No. 530,244.

To all whom it may concern:

Be it known that I, SAMUEL N. McCLEAN, a citizen of the United States, residing at Cleveland, in the county of Cuyahoga, 5 State of Ohio, have invented certain new and useful Improvements in Gas-Operated Guns, of which the following is a description, reference being had to the accompanying drawing and to the letters and figures 10 of reference marked thereon.

My invention relates to improvements in gas operated guns and more particularly to devices for controlling and utilizing the power of the powder gases to operate the 15 gun and to certain details of improvement in connection with the gas actuated breech actuating device by which the gun is operated.

The object of my invention is to provide 20 means for determining the pressure which the powder gas will exert upon the piston whereby the breech mechanism of a gas operated gun is operated; and to provide a device in which the gas by which the breech 25 mechanism of such a gun is operated will be mixed with a considerable quantity of air as it flows to the cylinder commonly included in such actuating devices, whereby any flame present will be snuffed out and 30 the temperature of the gas reduced.

A further object of my invention is to so 35 locate the operating cylinder and piston that a quantity of air unmixed with powder gas will be interposed between the heated gas and said piston, thereby protecting it from the high temperature of said gas.

Further objects of the invention are to 40 provide certain details in improvements in assembling and disassembling the parts of the breech actuating device with the gun barrel, and in the assembling and disassembling of the actuating parts of the said 45 actuating device; to provide a gas actuated device having a piston head which interlocks with the shaft to which it is attached; to 50 control the interlocking by means of the spring which returns the piston; to provide a cylinder head having vents and a screw threaded nut for opening, closing and adjusting these vents to secure the desired 55 pressure on the gas actuated device; to provide a gas actuated device having a piston head comprising a front and rear piston and an air chamber or an extinguishing chamber between the front and rear flanges of the

piston; to make the piston head cup shaped in order to deflect the flame of the powder gas in a curved direction; to provide an air chamber between the pistons for radiating purposes and to increase the radiating surface of the piston; to construct the cylinder of the gas actuated device so that it shall interlock with the chamber which connects the cylinder with the gun barrel, and to construct this cylinder so that it shall have a 60 sliding movement for opening up the gas actuated device to expose and clean the piston and to unlock and remove the piston head when desired, the cylinder part of the gas actuated device forming a sleeve which 65 telescopes to the rear on the outer side of the companion sleeve in which the returning spring moves; also to form the gas chamber so that it shall have a flange and groove 70 connection with the gun barrel and a retaining pin or other device by which it may be freed and slid out of engagement with its 75 companion flanges.

With these above and other objects hereinafter explained in view, my invention consists of and comprises the construction and combination of elements hereinafter described and particularly pointed out in the 80 claims.

Referring to the drawings—Figure 1 is a 85 longitudinal side elevation of a gun barrel equipped with my invention; Fig. 2 is a side elevation of the same parts on an enlarged scale showing the gas actuated device and associated parts in central section 90 and the piston head in elevation; Fig. 3 is a transverse sectional view through the barrel and gas chamber; Fig. 4 is a detail elevation of the piston head piston rod and returning spring and illustrates one form of 95 the construction for interlocking these parts; Fig. 5 is a detail view partly in section of the piston head and associated parts showing a modified form of the extinguishing chamber or air chamber between the front and 100 rear pistons. Fig. 6 is a detail view partly in section of the piston head and associated parts showing a modification in which the end of the spring passes through a hole in a lug on the piston bar into the piston head; 105 Fig. 7 is a detail view of the piston rod showing the actuating spring passing through a groove in the end of the rod to illustrate a modified construction for interlocking with the piston head; Fig. 8 is an 110

end elevation of Fig. 7; Fig. 9 is a side elevation partly in section of the piston rod showing the actuating spring passing through a hole bored through the end of the rod into an opening through which the spring passes.

In the drawings, 1 is the gun barrel having at its muzzle a gas collecting device 2, consisting of a chamber of greater interior diameter than the bore of the gun arranged in line with the bore and terminating at its outer end in an opening of substantially the same diameter as the bore of the gun.

3 is a gas chamber secured to the gas collecting device and communicating with the interior of the gas collecting device through a series of gas passages 4 of small diameter as shown. The gas chamber is held in position by means of its flanges 5 which engage flanges 6 on the gas collecting device, and a retaining pin 7, the construction being such that when the retaining pin 7 is withdrawn the gas chamber may readily be slid off from the flanges 6.

25 At its forward end the gas chamber 3 is provided with a head 8, having an extension 9 thereon which may be solid as shown in Fig. 1 or may have a port or opening 10 extending through it as shown in Fig. 2. 30 Ports or openings 11 are provided in the head 8, about the base of the extension 9. The extension 9 is screwthreaded and on it is mounted a nut 12, which if used with the extension having the opening 10 through it, 35 has an opening through its outer end in line with the port or opening 10. The nut 12 has a broad base adapted when the nut is screwed down to regulate or close the ports or openings 11. The nut is provided with any convenient means for turning it such as the recesses 13 to receive a spanner wrench. At its rear end the gas chamber 3 is provided with interior screw threads 14, preferably interrupted screw threads as shown in Fig.

40 2. In these screw threads 14 is received the forward end of a gas cylinder 15 having formed thereon screwthreads 16. The gas cylinder 15 is detachably secured at its rear end to the tube 17 which carries the piston rod 18 through which movement is conveyed to the breech mechanism. The detachable connection between the gas cylinder and the tube 17 may conveniently comprise a series of spring arms 19 extending rearward and having on their under sides projections 20 adapted to engage recesses 21 formed in the outer surface of the tube 17. The gas cylinder may also be provided at its forward end with a spring arm 22 having a recess 23 on its under side to engage a projection 24 on the outer surface of the rear end of the gas chamber 3. The gas cylinder is also preferably provided with recesses 25 to receive a spanner wrench for rotating it.

65 The interior diameter of the gas cylinder

is preferably the same as the interior diameter of the gas chamber 3. In the gas cylinder is located the piston 26 secured on the end of the piston rod 18, the piston being forced forward or returned to its original position after having been acted upon by the powder gas by a spring 27 coiled about the piston rod 18, within the tube 17, and having its rear end resting against a suitable abutment located adjacent the breech of the gun. The piston rod 18 is preferably hollow as shown and on its interior at its forward end is provided with interrupted screw threads 28 with which engage interrupted screwthreads 29 on a rearward extension 30 of the piston 26. In the piston 26 is formed a deep annular groove 31 dividing it into two portions, a forward portion 26' and a rearward portion 26², connected by a neck 26³. In the forward face 85 of the rearward portion 26² is preferably formed an annular groove 32, and in the forward face of the forward portion 26' is formed a circular recess 33. In the rear face of the rear portion 26² is formed a recess 34 to receive the end of the spring 27.

In order to prevent the spring 27 from uncoiling its end is engaged with retaining means on the end of the piston rod. The retaining means may be a pair of lugs 35, 95 between which the end of the spring is placed as shown in Figs. 2 and 4, or a recess 36 in the end of the rod in which the end of the spring is received as shown in Figs. 5, 7 and 8, or an apertured lug 37, through 100 which the end of the spring is thrust as shown in Fig. 6 or an aperture 38 in the end of the piston rod with a recess 39 leading to it as shown in Fig. 9.

In order to disassemble the parts of the device the gas cylinder 15 is unlocked from the gas chamber 3 by lifting the end of the spring arm 22 until its recess 23 is disengaged from the projection 24 and the gas cylinder then rotated until its interrupted screw threads 16 are free from engagement with the screw threads 14 of the gas chamber 3. The gas cylinder is then slid rearward on the tube 17 until the piston 26 and the end of the piston rod are exposed. By 115 then pressing the spring 27 rearward sufficiently to disengage its end from the recess 34 in the piston, the piston is unlocked and, by rotating it, the screwthreads of its extension 30 are disengaged from the companion screw threads in the end of the piston rod so that it may be taken off the end of the piston rod. By removing the retaining pin 7, the gas chamber may be slid off the flanges 6. As thus constructed, the entire 125 device may be readily assembled or disassembled without the use of tools other than a spanner or wrench.

It will be understood that after the gun is fired at the instant that the projectile is 130

about to leave the end of the gas collecting device 2, a portion of the burning gases of discharge under high pressure will pass through the passages 4 into the chamber 3. 5 The passages 4 being of small diameter will divide up the current of gases and will tend to snuff out or extinguish the flame. The gases passing into the chamber 3 to which air is admitted freely through the ports or 10 openings 10 and 11, will be mingled with the air reducing the temperature to some extent and tending to extinguish any flame which may pass through the passage 4. More or less of the gases will escape through the 15 openings 10 and 11, thus reducing the pressure in the gas chamber to the pressure desired for operating the breech mechanism through the piston and piston rod. The escape of the gases and the consequent reduction in pressure will be regulated by 20 means of the nut 12. By reason of the location of the piston in the gas cylinder a considerable distance in rear of the passages 4 as shown, there will always be a considerable 25 volume of air in front of the piston and this volume of air will, to some extent, serve as a cushion to lessen the shock of impact on the piston and will also protect the piston and spring from the heat of the gases. 30 As a further means for extinguishing the flame of the gases and preventing the temper of the spring from being affected by the flame of the gases, the piston, as above described, is formed in two parts with an annular recess between them so that any flame 35 passing the forward portion of the piston will be snuffed out in this recess. The annular groove 32 shown in Fig. 6, aids in this extinguishing of the flame by causing the 40 gases which pass into the groove 31 to eddy checking their movement and thus giving time for the flame to burn out or become extinguished.

The gas cylinder 15 as well as the barrel 45 of the gun is preferably knurled on its outer surface as shown to increase the radiating surface and thus to cool the cylinder and barrel and prevent overheating which would draw the temper of the steel or otherwise injure it. The knurling is preferably produced by the action of rolls by which the 50 surface is crushed and broken into innumerable sharp or jagged points, increasing the radiating surface two-and-one-half or more 55 times the surface of a smooth cylinder, the jagged points acting to throw off the heat much more rapidly than would a smooth surface and keeping the barrel and gas cylinder and contiguous parts sufficiently cool 60 to permit automatic firing to be kept up much longer than it could otherwise without injury from over heating.

It will, of course, be understood that I do not desire to be limited to the precise 65 details shown and described, it being obvious

that details may be modified without departing from the spirit of the invention.

Having thus described my invention, what I claim as new and desire to secure by Letters Patent, is—

1. In a gas operated gun, a barrel; a gas chamber; a permanently open passage leading from said barrel to said chamber; a permanently open passage leading from said chamber to the atmosphere; a regulating member located opposite the discharge end of said second passage; and means for adjusting said member with reference to said passage to thereby regulate the flow of air therethrough. 70

2. In a gas operated gun, a barrel; a gas chamber; a permanently open passage leading from said barrel to said chamber; a permanently open passage leading from said chamber to the atmosphere; a threaded member extending from the wall of said gas chamber and located adjacent said second passage; and a regulating member engaging said threaded member and adjustable thereon and having a portion extending opposite the discharge end of said second passage; whereby the flow of air through said passage may be regulated. 80

3. In a gas operated gun, a barrel; a gas chamber; a cylinder communicating with said chamber; a piston in said cylinder; a permanently open passage leading from said chamber to the atmosphere; and a permanently open passage leading from said barrel to said chamber at a point between 90 said cylinder and said passage leading to the atmosphere. 95

4. In a gas operated gun, a gas chamber communicating with the barrel and having openings in its forward end for access of air, a gas cylinder connected with the gas chamber, at its rear end, and a piston movable in said gas cylinder. 105

5. In a gas operated gun, a gas chamber communicating with the barrel and having 110 openings in its forward end for access of air, a gas cylinder connected with the gas chamber, at its rear end, and a piston movable in said gas cylinder, the piston being so located that an air space is left between it 115 and the gas cylinder.

6. In a gas operated gun, a barrel; a gas chamber detachably connected thereto; a passage connecting said barrel and chamber; a cylinder detachably connected with 120 said chamber and movable relatively thereto; means for guiding said cylinder in its movement away from the chamber; and a piston in said cylinder.

7. In a gas operated gun, a barrel; a gas chamber detachably connected thereto; a passage connecting said barrel and chamber; a cylinder detachably connected to said chamber and extending parallel with the barrel of the gun; said cylinder being rota- 125 130

table about its axis and also capable of longitudinal movement along its axis; means whereby rotary movement imparted to said cylinder will lock it to said chamber and 5 unlock it therefrom; means for guiding said cylinder in both its rotary and longitudinal movements; and a piston in said cylinder.

8. In a gas operated gun, a gas chamber communicating with the barrel and detachably connected thereto, a gas cylinder 10 detachably connected with the gas chamber, a piston movable within the gas cylinder, a piston rod, and a tube in which the piston rod is carried, the gas cylinder having a 15 sliding connection with the tube.

9. In a gas operated gun, a gas cylinder communicating with the gun barrel, a piston movable in the gas cylinder, a piston rod carrying the piston, the piston being 20 detachably connected with the piston rod, and means for locking the piston against detachment.

10. In a gas operated gun, a gas cylinder communicating with the gun barrel, a piston 25 movable in the gas cylinder, a piston rod carrying the piston, the piston having a screw connection with the piston rod, and means for locking the piston against rotation.

11. In a gas operated gun, a gas cylinder 30 communicating with the gun barrel, a piston movable in the gas cylinder, a piston rod carrying the piston, the piston having a screw connection with the piston rod, and 35 means for locking the piston against rotation, comprising a spring carried by the piston rod.

12. In a gas operated gun, a gas cylinder 40 communicating with the gun barrel, a piston movable in the gas cylinder, a piston rod carrying the piston, the piston having a screw connection with the piston rod, and 45 means for locking the piston against rotation, comprising a spring carried by the

piston rod having a projecting end engaging 45 a recess in the piston.

13. In a gas operated gun, a gas cylinder communicating with the barrel, a piston movable in the gas cylinder, a piston rod carrying the piston, a spring carried by the 50 piston rod, means on the piston rod for preventing rotation of the spring on the piston rod adapted to permit longitudinal movement of the end of the spring.

14. In a gas operated gun, a gas cylinder 55 communicating with the barrel, a piston movable in the gas cylinder, having a recess in its rear face, a piston rod to which the piston is so connected that it may be locked or released by rotating it, and means carried 60 by the piston rod adapted to engage the recess in the piston to hold it in locked position.

15. In a gas operated gun, a gas cylinder communicating with the barrel, a piston 65 movable in the gas cylinder having a recess in its rear face, a piston rod with which the piston is so connected that it may be locked or released by rotating it and a spring carried by the piston rod having its end 70 adapted to engage the recess in the piston and means carried by the piston rod adapted to prevent the end of the spring from rotating thereon.

16. In a gas operated gun, a gas cylinder 75 communicating with the barrel, a piston screwthreads adapted to receive the screwthreads formed thereon, a piston rod having screwthreads adapted to receive the screwthreads of the piston and means carried by 80 the piston rod adapted to engage the piston to prevent its rotation.

In testimony whereof I affix my signature, in presence of two witnesses.
